UNITED STATES PATENT OFFICE.

JOHN BUCHE, OF APPLE RIVER, ILLINOIS.

IMPROVEMENT IN BUCKLES.

Specification forming part of Letters Patent No. 121,325, dated November 28, 1871.

To all whom it may concern:

Be it known that I, JOHN BUCHE, of Apple River, in the county of Jo Daviess and State of Illinois, have invented a new and useful Improvement in Breech-Buckle; and I do hereby declare that the following is a full, clear, and exact description thereof, which will enable others skilled in the art to make and use the same, reference being had to the accompanying drawing forming part of this specification.

In the accompanying drawing, Figure 1 is a view of the buckle applied. Fig. 2 is a longitudinal section of Fig. 1 taken on the line *x x*. Fig. 3 is a cross-section of Fig. 1 taken on the line *y y*.

Similar letters of reference indicate corresponding parts.

My invention consists in the improvement of breech-buckles, as hereinafter fully described and subsequently pointed out in the claim.

A represents a hip-strap, and *B B* breeching-braces. *C* is the body, and *D* the ring, which together constitute my improved breeching-buckle.

E is a tongue hinged at *f* to side of buckle and having pin *g* in the center. The pin *g* passes through hole in strap *A*, which passes over the hinged tongue and under each end of buckle.

By slipping the strap back the tongue is released, and the strap may be lengthened, shortened, or withdrawn. The side straps *B B* are permanently attached to the ring *D*.

Having thus described all that is necessary to a full understanding of my invention, what I desire to secure by Letters Patent is—

1. The body *C* of a breech-buckle, having hinged tongue *E* carrying the pin *g* applied crosswise thereto, as and for the purpose specified.

2. The ring *D* and the body *C*, having hinged tongue *E* with pin *g*, constructed and arranged as described, to form a new article of manufacture.

JOHN BUCHE.
